PRESSURE-CONTROLLED VALVE.

1,138,278.

Specification of Letters Patent.

Patented May 4, 1915.

Application filed September 25, 1913. Serial No. 791,709.

To all whom it may concern:

Be it known that we, JOHN H. CASTLE and WILLIAM G. ROGERS, citizens of the United States, residing at Painted Post, in the county of Steuben and State of New York, have invented a certain new and useful Improvement in Pressure-Controlled Valves, of which the following is a specification.

10 This invention relates to a pressure controlled valve for use with regulating mechanism for compressors, or similar purposes, and more particularly to a valve of the type wherein at a certain predetermined receiver pressure the valve operates to admit such receiver pressure to the regulating mechanism, until the receiver pressure again falls a certain amount below that required to operate the valve, when the valve returns to 15 its original position allowing the regulating mechanism to exhaust to atmospheric pressure.

Our invention has for its object the production of a simple and effective means for 20 accomplishing this purpose.

A further object is to provide means for adjusting the valve not only to operate at different receiver pressures but also to regulate the pressure drop necessary to allow 25 the valve to return to its original position after having been opened by a predetermined receiver pressure.

With these objects in view we have devised a valve a practical embodiment of 30 which is shown in the accompanying drawing which shows a longitudinal section through the valve in connection with a diagrammatic sketch of a compressor system in which the valve operates an electric controller switch.

As shown, the system comprises a compressor 1 driven by a motor 2 controlled by a switch 3. This switch is operated by a motor comprising a cylinder 4 in which reciprocates a piston 5 attached to the moving element 6 of the switch. A spring 7 normally holds the switch in closed position and the switch is opened by fluid pressure conveyed by a pipe 8 from the valve 9 which forms the subject of this application.

The valve 9 consists of a generally cylindrical valve chest 10 in the central part of which is a valve chamber 11 from which leads the pipe 8. From one end of the valve chamber 11 a cylindrical passage 12 leads to the atmosphere as will be further described. This cylindrical passage is provided at its inner end, where it opens into the valve chest 11, with a beveled valve seat 13. Adjustably threaded into the other end of the valve chest 10 is a plug 14 provided with a cylindrical passage 15 through it which is of less diameter than the passage 12. The inner end of the plug 14 is tapered down providing a narrow annular valve seat 16 opposite to and aligned with the larger valve seat 13. To the outer end of the plug 14 a pipe 17 leads from the receiver 18 into which the compressor 1 discharges. Situated in the valve chamber 11 is a double ended valve 19 provided on one end with a beveled flange 20 adapted to seat against the valve seat 13 and on the other end with a flange 21. The flange 21 is of slightly less diameter than the valve chest 11 and is provided on its outer face near the periphery with an annular depression 22. Inside of the depression 22 is a valve surface 23 which seats against the inner end 16 of the plug 14, the two surfaces being ground to produce a tight fit. The valve 19 is kept in alignment by guides 24 and 25 sliding respectively in passages 12 and 15. Sliding in chamber 12 in contact with the guide 24 is a spring guide 26 against which presses 27 a spring 28 held in place by a spring cup 29 adjustably threaded into the end of valve chest 10. A vent passage 29, through the end of the spring cup 28, affords communication from the passage 12 to the atmosphere.

In operation the tension of the spring 27 is so regulated that it will counter-balance the receiver pressure exerted on the valve 19 through the passage 15 this pressure being effective on an area of the valve equivalent to the cross section of the passage 15. At a certain pressure however, determined by the adjustment of the spring 27, the receiver pressure will overcome the pressure 100

of the spring and move the valve away from the seat 16. The air from the receiver will then rush into passage 11 and by its impact on the flange 21 will move the valve 5 so that the valve surface 20 seats against the valve seat 13, the receiver air at the same time passing around the edges of the flange 21 into the valve chest 11 and thence through the pipe 8 into the cylinder 4. This 10 will raise the piston 5 breaking the switch connection 3 and thus cutting off the motor 2 of the compressor. As the valve seat 13 and the passage 12 leading therefrom are larger than the valve seat 16 and its passage 15, the receiver pressure tending to hold the valve against the seat 13 will be exerted upon a greater area than that on which it acts to move the valve away from seat 16 to admit the receiver pressure to the 20 valve chest. This area has been described in the claims as the "holding surface," while the area of the valve against which the receiver pressure is exerted to move it from the seat 16 has been called the "operating 25 surface." As the "holding surface" is larger than the "operating surface" the pressure in the receiver must drop due to the non operation of the compressor to an amount dependent on the difference in the 30 area of these two surfaces before the valve will return.

In the present device the pressure drop required to allow the valve to return to its original position can be varied by varying 35 the position of the plug 14. If this plug is adjusted outwardly for instance, the valve 19 will have a greater travel in going from valve seat 16 to valve seat 13 and hence will compress the spring 27 to a greater degree, 40 assuming of course that the spring 27 in both cases had the same initial compression, and consequently the spring will start the backward movement of the valve with a less pressure drop. By having therefore not 45 only the tension of the spring adjustable but the distance of the valve seats from each other also adjustable, the device can be set so that within the limits imposed by its construction, the valve 19 will move to admit 50 receiver pressure into the valve chest 11 at any determined pressure and will return to its original position after the receiver pressure has dropped any predetermined amount. When the receiver pressure does 55 thus fall so that the valve 19 again seats against valve seat 16 the valve chest 11 will be open to the atmosphere through the passage 12 and vent passage 29 allowing the fluid under pressure to escape from the 60 cylinder 4 thus causing the spring 7 to force down the piston 5 and close the switch connection 3, again starting the motor to drive the compressor. Although the valve is here shown in connection with a motor operating

an electric switch for controlling a compressor motor it is evident that the valve is adapted for use with any compressor regulator or like mechanism for the operation of which it is necessary to admit fluid when the receiver pressure reaches a certain value 70 and to exhaust the admitted fluid when the receiver pressure falls below a certain value.

It is to be understood that the present showing and description discloses only one specified modification of our invention and 75 other forms and modifications are included in the spirit and scope of the invention as expressed in the claims.

What we claim is:

1. In a pressure controlled valve, a valve 80 chest, alined inlet and exhaust openings therein having valve seats, means to adjust the relative distance of said seats, a movable valve element having portions adapted to alternately seat on said valve seats, a 85 spring tending to hold said valve element against said inlet valve seat, an operating surface on said valve element exposed to said inlet opening of an area sufficient to overcome said spring and open said inlet, 90 valve at a predetermined inlet pressure, a flange on said valve element adapted to utilize the velocity of the inlet current and continue the movement of said valve element to seat against said exhaust seat, and a holding surface on said valve element, exposed to said inlet pressure, of an area greater than said operating surface.

2. In a pressure controlled valve, a valve 100 chest, alined inlet and exhaust openings therein having valve seats, means to adjust the relative distance of said seats, a movable valve element having portions adapted to alternately seat on said valve seats, a spring 105 tending to hold said valve element against said inlet valve seat, means to adjust the tension of said spring, an operating surface on said valve element exposed to said inlet opening of an area sufficient to overcome said spring and open said inlet valve at a 110 predetermined inlet pressure, a flange on said valve element adapted to utilize the velocity of the inlet current and continue the movement of said valve element to seat against said exhaust seat, and a holding surface on said valve element exposed to said inlet pressure, of an area greater than said operating surface.

3. In a pressure controlled valve, a valve 115 chest, an inlet opening into said valve chest, an exhaust opening from said valve chest of larger area than said inlet opening, a valve having portions adapted to alternately close said openings, a spring tending to hold said valve to close said inlet opening, and means 120 for adjusting the pressure of said spring and the amount of movement of said valve.

4. In a pressure controlled valve, a valve

chest, an inlet opening into said valve chest, an exhaust opening from said valve chest of larger area than said inlet opening, a valve having portions adapted to alternately close 5 said openings, a spring tending to hold said valve to close said inlet opening, and means for varying the travel of said valve.

In testimony whereof we have hereunto set our hands.

JOHN H. CASTLE.
